HYDROCARBON TREATING PROCESS

Hervey H. Voge, Berkeley, George M. Good, Albany, and Bernard S. Greensfelder, Oakland, Calif., assignors to Shell Development Company, San Francisco, Calif., a corporation of Delaware

Application August 24, 1946, Serial No. 692,882

8 Claims. (Cl. 260—683.6)

1

This invention relates to the separation and/or production of useful products from lower boiling olefins, especially olefins having from 4 to 6 carbon atoms and hydrocarbon mixtures containing substantial quantities of such olefins. In one embodiment of the invention, normal olefins are separated from hydrocarbon mixtures containing them as well as their branched chain isomers through selective conversion of the branched chain isomers into saturated hydrocarbons which may be separated from the normal olefins by conventional separation processes. In other embodiments of the invention this selective conversion of branched chain olefins to saturated hydrocarbons is utilized to produce an iso-paraffin and/or gasoline.

An object of the invention is to provide a new and improved method for the separation of normal olefins from a hydrocarbon mixture containing the same in admixture with an isomeric branched chain olefin. Thus, an object is to provide a method for the separation of normal butylenes from refinery butylene fractions.

Another object of the invention is to provide a method for the production of iso-paraffins. Thus, an object of the invention is to provide a method for the production of isobutane from butylene or refinery butylene fractions and the production of isopentane from amylene fractions.

A further object of the invention is to provide a method for the production of improved yields of alkylate gasoline having improved volatility from refinery butylene fractions.

These and other objects which will be apparent in the description of the invention and its uses are attained through the catalytic treatment of suitable olefinic fractions under conditions to more or less selectively convert the olefins having a branched chain into the corresponding iso-paraffins. Thus, the process of the invention in its more general aspect involves reacting an olefinic hydrocarbon fraction containing substantial amounts of a normal olefin and an isomeric branched chain olefin in the vapor phase in the presence of a cracking catalyst at a temperature below that affording cracking of the hydrocarbon mixture but above that at which substantial polymerization to higher boiling olefins takes place and for a time adjusted to selectively convert branched chain olefins to saturated products consisting largely of the corresponding branched chain paraffin.

The process is generally applicable to the treatment of lower boiling hydrocarbon fractions such as are commonly encountered in various refinery

2

operations. Preferred fractions are those having from 4 to about 6 carbon atoms, i. e. boiling below about 70° C. Particularly suitable materials are the so-called refinery butylene and amylene fractions. In general, separation of one or more of the components of such fractions is possible by the application of conventional methods. However, a complete separation is too difficult to be feasible except on a small scale for special purposes. The usual refinery butylene fraction represents the simplest case because of the fewer possible isomers. In this simplest case, certain separations can be made quite readily. However, the separation of butene-1 from isobutylene is difficult. These two isomeric olefins boil within 1° of one another and are generally quite similar in properties. However, a practical means for this separation is desirable, since these two olefins are desired separately for different purposes. The normal olefin is desired, for example, as a starting material for the production of butadiene, whereas the isobutylene is desired separately as a starting material in various syntheses.

The catalyst used in the process of the present invention is a cracking catalyst. The term "cracking catalyst" is meant to designate that group of catalysts which is active in catalyzing the scission of C-C bonds, but which has no appreciable ability to catalyze the addition of hydrogen to an olefinic bond. Examples of such catalysts are the complex silica-alumina, silica-magnesia, silica-zirconia-alumina, and alumina-boria cracking catalysts and the activated clay cracking catalysts. Any of the various known cracking catalysts of this general type (frequently referred to as clay-type cracking catalysts) may be used. The usual cracking catalysts rarely contain a hydrogenating component. However, occasionally a hydrogenating component (e. g. Mo, W, Co) is incorporated in a small amount to aid in the catalyst regeneration or for other reasons. Such catalysts may be used in the process of the present invention, in the usual case where there is no appreciable free hydrogen present in the reaction zone. Ordinary hydrogenation with free hydrogen is avoided. Such hydrogenation, it is found, gives a totally different result.

The conditions of treating in the process of the present invention are important and critical. At high temperatures the cracking catalyst causes cracking of the olefinic feed. At low temperatures the cracking catalyst causes polymerization of the olefins to high boiling polymers. The applicable temperatures constitute that range which lies between these two extremes. The limits of

temperature, although critical, cannot be stated to lie within definite limits for the general case since the limits depend upon the space velocity, upon the particular olefin fraction treated, upon the particular catalyst used, and to some extent upon the purpose of the treatment. The governing factors are analogous to those in catalytic cracking, which factors are well known and understood. The conditions are adjusted in the known manner and according to known principles such that the temperature is below that affording cracking of the hydrocarbon mixture, but above that at which substantial polymerization to higher boiling olefins takes place. The contact time is adjusted to decrease the bromine number to a value corresponding approximately to the content of normal olefin in the product. While the critical limits of the applicable ranges of conditions cannot be defined in absolute values for the general case, the following conditions are generally within the critical range and may be considered as approximations of the applicable range:

	C ₄ Fraction	C ₆ Fraction
Minimum temperature, °C.....	325	300
Maximum temperature, °C.....	450	425
Minimum LHSV.....	0.3	0.3
Maximum LHSV.....	3.0	2.0

(Liquid hourly space velocity—LHSV—is defined as the volumes of olefinic fraction, measured as a liquid, which is passed in contact with a given volume of the catalyst per hour.) When the process is carried out in the presence of a suitable hydrogen donor, as will be described below, considerably higher liquid hourly space velocities up to about double those just given may be used. The liquid hourly space velocity of the total material fed to the reaction zone in this case is still higher depending upon the amount of hydrogen donor material included. The operation is preferably carried out at pressures from atmospheric pressure up to about 10 atmospheres. The indicated liquid hourly space velocities are for substantially atmospheric pressure operation. As the pressure is increased, the liquid hourly space velocity should be adjusted in the known manner to afford an approximately equivalent contact time.

The contact time (LHSV) is adjusted such that the branched chain olefin or olefins in the feed are substantially completely converted. In practice some isomerization of the olefins usually takes place and as a consequence it is not possible to produce a product completely free of branched chain olefins. However, when the branched chain olefins in the feed have been substantially completely converted only a minor amount of branched chain olefins will be found in the product. The adjustment and control of the contact time (LHSV) may be made through correlation with the bromine number. The bromine number, which is easily determined by the known methods, is a function of the total olefin content of the sample. Thus, the liquid hourly space velocity may be adjusted such that the bromine number of the product corresponds approximately to the content of normal olefin therein. When this condition pertains, the branched chain olefins (except for the minor residue produced by isomerization as explained above) will have been substantially completely reacted; a decrease in the liquid hourly space velocity will cause reaction of the normal olefins; an increase in the liquid hourly space velocity

will give an incompletely converted product containing considerable amounts of branched chain olefins, from which product the desired normal olefins cannot be easily separated. When the conditions are properly adjusted the product contains only the above-mentioned minor amount of residual branched chain olefins and the desired normal olefins may be readily separated from the reaction mixture by conventional methods.

The separation of the residual normal olefins from the isoparaffin produced may be effected by any one of a number of methods. In some cases a sharp fractionation may suffice. The preferred method is, however, through extraction of the normal olefins. Any one of the large number of known solvents may be used for this purpose. Examples of a few suitable solvents are sulfur dioxide, furfural, acetone-water, and sulfolane. Also, combination processes such as extractive distillation may be applied.

In some cases it will not be desired to recover the normal olefins per se. Thus, the normal olefins in the reaction product may be reacted or converted into a desired product instead of being separated. This allows the process of the invention to be advantageously applied for the production of gasoline. For example, the normal olefins may be polymerized or alkylated in situ. Such applications of the process of the invention are described in more detail later in connection with the drawings.

In the present process the branched chain olefin is selectively reacted and the primary reaction product is the corresponding branched chain paraffin. Thus, the process of the invention may, if desired, be considered from the standpoint of this reaction product, i.e. it may be utilized as a means of producing branched chain paraffins. For example, in combination with a dehydrogenation step, it may be utilized to produce (separate) normal butylenes and isobutane from refinery butane-butylenes fractions, or, in combination with an olefin isomerization step, the entire normal butylenes may be utilized in the production of isobutane. Details of such applications are explained below in connection with the drawings.

The formation of isoparaffin from the corresponding branched chain olefin in the present process takes place through a self-saturation reaction. In the simple case the necessary hydrogen comes from the conversion of part of the reactant to a carbonaceous residue. This carbonaceous residue is removed from the catalyst by burning in the known manner. As a consequence of this reaction, the yields of product are always less than 100%. The yield may be improved, however, by the application of a material which under the conditions will donate hydrogen more readily than the olefinic fraction treated. Cyclohexane, cyclohexene and related hydrocarbons, although known to be good sources of hydrogen, are of no particular value for this purpose. It is found, however, that their polycyclic counterparts such as decahydronaphthalene, tetrahydronaphthalene and related polycyclic hydroaromatic compounds may be advantageously used. Thus, if such material or a fraction containing substantial amounts of such material is available, it may be mixed with the olefinic feed to the reaction zone. In view of the high boiling point of such materials, they may be easily separated from the reaction product and cause no difficulty in the separation of the desired normal olefin. If a large supply of such

material is not available, the recovered material may be hydrogenated in a separate step using a conventional hydrogenation catalyst and free hydrogen and then reused.

Various features of the process of the invention and its modes of application will perhaps be better understood upon consideration of the following description of more specific applications. In the description, reference is had to the attached drawings wherein process flows are shown by means of conventional diagrams, and wherein:

Figure I illustrates an application of the process for the separation of a monoolefin from an olefinic hydrocarbon fraction containing the normal olefin in admixture with an isomeric branched chain olefin;

Figure II illustrates an application of the process for the production of alkylate gasoline from an olefinic fraction;

Figure III illustrates a modified process for the production of normal pentenes and isopentane from refinery pentane-amylenes fractions; and

Figure IV illustrates a modified process for the production of an isoparaffin from a corresponding olefin.

These figures are schematic and do not show all details, as, for instance, provision for removal of the light gases always formed in small amounts in such processes.

Referring to the drawing, Figure I, the olefinic feed, for instance a refinery butane-butylene fraction having the following analysis:

	Mole per cent
Isobutylene	23
Normal butylenes	43
Isobutane	20
Normal butane	14

entering via line 1, is forced by pump 2 through coil 4 of heater 3 wherein it is heated to the desired reaction temperature, for instance 400° C. The pre-heated charge then passes via line 5 to one or two of the reactors 6, 7 and 8. Although only one or two reactors may be used, it is preferable to employ at least three reactors since this allows two reactors to be used continuously while the third is undergoing regeneration. Air or other oxidizing gas for regeneration enters via manifold line 10. The spent regeneration gas is removed through manifold line 11. Reactors 6, 7 and 8 are filled with a suitable cracking catalyst such, for example, as pellets of the synthetic silica-alumina composite cracking catalyst or the treated clay cracking catalyst now in common use. An excellent catalyst can be simply and cheaply prepared by impregnating activated bauxite with silica or boric oxide. The reaction is carried out at a temperature between about 325° C. and 450° C. and at a pressure of about 30 p. s. i. g. The liquid hourly space velocity is adjusted at about 1.5 such that the olefin content of the product in manifold line 9 is about 40%, as determined by the bromine number.

The product withdrawn from the reactor via line 9 is passed to extractor 12. Cooled solvent, for example, sulfolane, is introduced into the top of extractor 12 via line 13 and passes counter-current to the feed. A substantially saturated product consisting predominantly of isobutane is withdrawn from the top of extractor 12 via line 14. The fat solvent is withdrawn from the bottom of extractor 12 and passed via pump 15

into stripper 16. Heat for stripping may be supplied to the stripper or to the feed as by heater 17. The stripped solvent is withdrawn from the bottom of stripper 16 and recirculated after cooling to the extractor. The stripped fraction consisting essentially of normal butylenes is recovered from the overhead product of stripper 16 via line 18.

In the embodiment illustrated in Figure II, the process is utilized to produce superior yields of alkylate gasoline having improved volatility. The usual refinery butane-butylene fraction, for instance having the analysis shown above, is suitable for alkylation only if a large supply of isobutane is available. In most refineries, however, there is not enough isobutane to balance the olefine. In many cases the excess olefin is therefore polymerized. In the process illustrated, excellent yields of alkylate may be produced from the refinery butane-butylene fractions without resort to extraneous sources of material. Thus, the necessary balance between the olefin and isobutane is established in the feed by the present process. Also, since in the present process the isobutane is produced by selective reaction of the isobutylene, the alkylate is produced essentially from normal butylenes. This gives a superior alkylate product. Also, the conditions in the present process may be easily adjusted to give a minor amount of intermediate boiling isoparaffins which enhance the volatility of the alkylate.

Referring to Figure II, the feed, for example, a refinery butane-butylene fraction such as mentioned above, entering via line 21, is commingled with a hydrogenated fraction rich in hydrogenated polycyclic aromatic hydrocarbons in line 22. The mixture is forced by pump 23 through preheater coil 24 in furnace 25. The feed preheated to about 400° C. passes via line 26 to one or more of the catalytic reactors 27, 28 and 29. Reactors 27, 28 and 29 are filled with granules of a solid cracking catalyst, for example, on alumina which is activated and impregnated with 15% by weight B₂O₃. The conditions are regulated as described in connection with the operation in Figure I. The product withdrawn via line 30 and containing normal butylenes, isobutylene, a small amount of gasoline and heavy oil is passed to fractionator 31 wherein the heavy oil is separated as a bottom product which is withdrawn via line 32. This heavy oil is charged to reactor 33 wherein it is hydrogenated with hydrogen introduced via line 34. Fresh polycyclic aromatic or hydroaromatic hydrocarbons may also be introduced via line 34. Reactor 33 is filled with any one of the many known applicable hydrogenation catalysts. A suitable catalyst by way of example is a pelleted mixture of sulfides of tungsten and nickel. With this catalyst typical conditions by way of example are as follows: temperature—350° C.; pressure—700 p. s. i. g.; LHSV—1; and an excess of hydrogen. The product passes via line 35 to separator 36 wherein dissolved hydrogen is separated and withdrawn via line 37. The hydrogenated product is then commingled with the feed and passed to the heater via line 22 and pump 23 as described.

The overhead product from fractionator 31 is passed via line 38 to a fractionator 39 wherein the C₄ fraction is separated overhead from a light gasoline fraction which is withdrawn from the bottom via line 40. The overhead C₄ fraction is passed via line 41 to fractionator 48. Normal butane is removed as a product of the process

via line 49. Isobutane is removed via line 50, cooler 51, surge tank 52, and is passed by pump 53 and line 54 to the alkylation unit. In the alkylation unit 42 normal butylenes and isobutane are caused to react through the agency of a suitable alkylation catalyst. The alkylation step may be carried out through any of the conventional processes. The alkylated product is passed via line 43 to fractionator 44 wherein it is separated into alkylate and lighter components. The alkylate is withdrawn from the bottom via line 45. This product is blended with the gasoline from line 40 and the blend is withdrawn as alkylate gasoline via line 46. The lighter fraction is passed via line 47 to fractionator 48.

In the modification of the process illustrated in Figure III, the feed, for example, a refinery pentane-amylenes fraction having the following approximate analysis:

	Mole per cent
Isoa nylenes	37
Normal amylenes	28
Isopentane	17
Normal pentane	18

enters via line 61. This feed is commingled with a mixture of hydrogenated heavy oil and amylenes introduced via line 62. The mixture is passed through coils of heater 64 wherein it is preheated to about 350° C. The preheated mixture passes via line 65 to one or more of reactors 66, 67 and 68. Reactors 66, 67 and 68 are filled with granules of a cracking catalyst, for example, the treated clay catalyst produced by the Filtral Corporation. The temperature may be, for example, 400° C. The liquid hourly space velocity with respect to the olefinic feed may be about 3.9, and the liquid hourly space velocity with respect to the total feed to the reaction zone may be about 8. Under these conditions the branched chain amylenes are not only converted selectively to the corresponding saturated compounds, but an appreciable amount of isomerization of the normal amylenes to branched chain amylenes takes place. The product leaving the reactors via manifold line 69 passes to a fractionator 70 wherein a heavy fraction containing polycyclic aromatic hydrocarbons is separated. This heavy fraction is removed by line 71 and passes to reactor 72 wherein it is hydrogenated with hydrogen introduced via line 73. The product passes via line 74 to a separator 75. Recovered hydrogen is removed by line 76 and recycled or withdrawn as desired. The hydrogenated product containing substantial amounts of hydrogenated polycyclic aromatic hydrocarbons is passed via lines 77 and 62 to the feed line wherein it commingles with the feed entering the preheater. If desired, fresh hydrogenated polycyclic aromatics may be introduced with the feed via line 61.

The overhead fraction from fractionator 70 is passed to fractionator 78. In fractionator 78 gasoline components produced in the process by a minor amount of cracking and destructive hydrogenation of the heavy recycled stock are separated as a bottom fraction which is withdrawn via line 79. The remainder consisting essentially of C₅ hydrocarbon is passed via line 80 to extractor 81, wherein it is contacted with a solvent which is selective for olefins, for example, dimethylsulfolane. A raffinate passes overhead via line 82 to a fractionator 83. The extract phase is passed via line 84 to a stripper 85,

The fraction consisting of extracted olefins (mostly normal amylenes) is recovered overhead via line 86 as a product of the process. The fraction fed to fractionator 83 consists largely of normal and isopentane. The isopentane is removed overhead via line 87 as a product of the process. The normal pentane is removed from fractionator 83 via line 88 and passed through coil 89 of heater 90 wherein it is preheated to a dehydrogenation temperature, for example, 550° C. The preheated fraction in the vapor phase is passed via line 91 to one or more of reactors 92 and 93. These reactors are filled with granules of the dehydrogenation catalyst such, for example, as alumina which is activated and impregnated with chromium oxide and/or molybdenum oxide. Manifold lines 94 and 95 are for the introduction and withdrawal of regeneration gas. The product withdrawn from reactor 92 and/or 93 via line 96 contains hydrogen, amylenes and pentanes. This product is passed through a separator 97, separated hydrogen is passed to the hydrogenation reactor 72 via lines 98 and 73. The pentane-amylenes product is withdrawn via line 99 and commingled with the hydrogenated cycled oil in line 62.

In an alternative process where it is desired to produce more normal amylenes and less branched chain pentanes, all or a part of the material in line 99 is passed via valved branch line 100 into the feed line to the extractor 81.

In the modification illustrated in Figure IV, the entire feed, except for the unavoidable losses to coke, etc., is converted into the desired iso-paraffin.

Referring to Figure IV, the feed, for example, a refinery pentane-amylenes fraction, is charged via line 110 and pump 111 to coil 112 in a heater 113, wherein it is preheated to, for example, 400° C. The preheated feed in line 114 is commingled with a fraction from line 115 and the mixture is passed to one or more of reactors 116, 117 and 118. These reactors are filled with cracking catalyst and are operated as described in connection with the other figures to afford reaction of the branched chain olefins without appreciable cracking or polymerization. The reaction product passes via line 119 to extractor 120. Extractor 120 and stripper 121 are operated as described in connection with Figure I. The raffinate (paraffinic compounds of the product containing the isoparaffins produced in the reactors 116, 117 and/or 118) is withdrawn as an overhead product of extractor 120 via line 122. The olefinic components of the product (extract) consisting essentially of normal olefins are separated from the fat solvent in stripper 121 and are removed overhead via line 123, cooler 124 and surge tank 125. This fraction is carried by line 126 and pump 127 to heating coil 128 in heater 129 wherein it is preheated to an isomerization temperature, for example, 475° C., and then passed via line 130 to reactor 131. Reactor 131 is filled with a catalyst effective for the isomerization of normal olefins to the isoolefins. Any of the known catalysts suitable for this purpose may be used. One suitable catalyst by way of example is alumina which is activated and has been acidified by a thorough washing with aqueous hydrochloric acid. The reaction product consisting essentially of branched chain olefins and unconverted normal olefins is commingled with the feed in line 114 as described and serves to enrich the feed with isoolefins, thereby increasing the efficiency in reactors 116,

117 and 118. The cracking catalyst used in reactors 116, 117 and 118 generally has an appreciable isomerization ability. Therefore, the entire amount of olefin may be converted by repeated recycling of the normal olefin to these reactors. However, the conditions in reactors 116, 117 and 118 are not necessarily optimum for olefin isomerization and consequently the application of the separate isomerization reactor 131 allows a more efficient process.

The invention claimed is:

1. Process for the production of useful products from C₄ fractions containing normal butylenes and isobutylene which comprises treating the C₄ fraction in the presence of an added fraction rich in polycyclic hydroaromatic hydrocarbons in the vapor phase with a cracking catalyst of the group consisting of silica-alumina, silica-magnesia, silica-zirconia-alumina and alumina-boria cracking catalysts and the activated clay cracking catalysts at a temperature between 325° C. and 450° C. and at a pressure between 1 and 10 atmospheres, said conditions being correlated in the known manner within said ranges to avoid substantial cracking of said olefins, discontinuing the treatment when the bromine number of the resulting product corresponds to the content of normal butylenes in the mixture whereby the said isobutylene is selectively converted to isobutane, separating the product into a heavy oil containing polycyclic aromatic hydrocarbons, normally gaseous products and a gasoline fraction, hydrogenating said separated heavy oil and cycling it to the C₄ feed as the added fraction rich in polycyclic hydroaromatic hydrocarbons, subjecting the normally gaseous fraction to an alkylation treatment to produce an alkylated product boiling within the gasoline range, and blending the product of alkylation with said separated gasoline fraction to produce a substantially saturated low density stable gasoline having good anti-knock rating and a greater volatility than that of the product of alkylation alone.

2. Process for the production of useful products from hydrocarbon mixtures containing normal and branched chain olefins having from 4 to about 6 carbon atoms which comprises treating the hydrocarbon mixture enriched in branched chain olefins in the vapor phase with a cracking catalyst of the group consisting of silica-alumina, silica-magnesia, silica-zirconia-alumina and alumina-boria cracking catalysts and the activated clay cracking catalysts at a temperature between 300° C. and 450° C. and at a pressure between 1 and 10 atmospheres, said conditions being correlated in the known manner within said ranges to avoid substantial cracking of said olefins, discontinuing said treatment when the bromine number of the resulting product corresponds to the content of normal olefins in the mixture whereby the said branched chain olefins are selectively converted to the corresponding isoparaffins, separating the product by solvent extraction into a saturated fraction consisting largely of branched chain paraffins and an unsaturated fraction consisting largely of unchanged normal olefins, subjecting said fraction consisting largely of normal olefins to a catalytic isomerization treatment to produce a mixture of normal and branched chain olefins rich in branched chain olefins, and utilizing said isomerized mixture to enrich the above said hydrocarbon mixture with branched chain olefins as above specified.

3. Process for the production of useful products from hydrocarbon mixtures containing normal

and branched chain olefins having from 4 to about 6 carbon atoms which comprises treating such olefinic feed in the presence of an added higher boiling fraction rich in polycyclic hydroaromatic hydrocarbons and in the presence of added branched chain olefin produced as herein-after set forth in the vapor phase with a cracking catalyst of the group consisting of silica-alumina, silica-magnesia, silica-zirconia-alumina and alumina-boria cracking catalysts and the activated clay cracking catalysts at a temperature between 300° C. and 450° C. and at a pressure between 1 and 10 atmospheres, said conditions being correlated in the known manner within said ranges to avoid substantial cracking of said olefins, discontinuing said treatment when the bromine number of the resulting product corresponds to the content of said normal olefins in the mixture whereby the said branched chain olefins are selectively converted to the corresponding branched chain paraffins, separating the product by solvent extraction into a saturated fraction consisting largely of branched chain paraffins and an unsaturated fraction consisting largely of unchanged normal olefins, subjecting said fraction consisting largely of normal olefins to a catalytic isomerization treatment to produce a mixture of normal and branched chain olefins rich in branched chain olefins, and treating said mixture in admixture with the olefinic feed as described above.

4. Process for the production of useful products from butane-butylenes fractions which comprises treating a butane-butylenes fraction in the presence of an added butane-butylenes fraction produced as herein-after specified in the vapor phase with a cracking catalyst of the group consisting of silica-alumina, silica-magnesia, silica-zirconia-alumina and alumina-boria cracking catalysts and the activated clay cracking catalysts at a temperature between 325° C. and 450° C. and at a pressure between 1 and 10 atmospheres, said conditions being correlated in the known manner within said ranges to avoid substantial cracking of said olefins, discontinuing said treatment when the bromine number of the resulting product corresponds to the content of normal butylenes in the mixture whereby the isobutylene in the mixture is selectively converted to isobutane, separating the product by solvent extraction into a saturated fraction consisting largely of isobutane and unconverted normal butane and an unsaturated fraction consisting largely of unchanged normal butylenes, separating said saturated fraction by fractional distillation into an isobutane fraction and a normal butane fraction, subjecting said normal butane fraction to a catalytic dehydrogenation, and commingling the product of said dehydrogenation with said butane-butylenes fraction specified above.

5. The process which comprises contacting a mixture of a straight chain olefin and an isomeric branched chain olefin having from 4 to 6 carbon atoms with a cracking catalyst of the group consisting of silica-alumina, silica-magnesia, silica-zirconia-alumina and alumina-boria cracking catalysts and the activated clay cracking catalysts at a temperature between 300° C. and 450° C. and at a pressure between 1 and 10 atmospheres, said conditions being correlated in the known manner within said ranges to avoid substantial cracking of said olefins, discontinuing said contact when the bromine number of the resulting product corresponds to the content of said straight chain olefin in the mixture whereby the said branched

chain olefin is selectively converted to the corresponding isoparaffin, and recovering the said straight chain olefin in concentrated form from the isoparaffin so produced.

6. The process which comprises contacting a mixture of a straight chain olefin and an isomeric branched chain olefin having from 4 to 6 carbon atoms in the presence of an added polycyclic hydroaromatic hydrocarbon with a cracking catalyst of the group consisting of silica-alumina, silica-magnesia, silica-zirconia-alumina and alumina-boria cracking catalysts and the activated clay cracking catalysts at a temperature between 300° C. and 450° C. and at a pressure between 1 and 10 atmospheres, said conditions being correlated in the known manner within said ranges to avoid substantial cracking of said olefins, discontinuing said contact when the bromine number of the resulting product corresponds to the content of said straight chain olefin in the mixture whereby the said branched chain olefin is selectively converted to the corresponding isoparaffin, and recovering the said straight chain olefin in concentrated form from the isoparaffin so produced.

7. A process which comprises contacting a C₄ fraction containing substantial amounts of normal butylenes and isobutylene with a cracking catalyst of the group consisting of silica-alumina, silica-magnesia, silica-zirconia-alumina and alumina-boria cracking catalysts and the activated clay cracking catalysts at a temperature between 325° C. and 450° C. and at a pressure between 1 and 10 atmospheres, said conditions being correlated in the known manner within said ranges to avoid substantial cracking of said olefins, discontinuing said contact when the bromine number of the resulting product corresponds to the content of said normal butylenes in the mixture whereby said isobutylene is selectively converted

to isobutane, and recovering the said normal butylenes in concentrated form from the isobutane so produced.

8. The process which comprises treating a C₅ fraction containing substantial amounts of normal amylenes and branched chain amylenes with a cracking catalyst of the group consisting of silica-alumina, silica-magnesia, silica-zirconia-alumina and alumina-boria cracking catalysts and the activated clay cracking catalysts at a temperature between 300° C. and 425° C. at a pressure between 1 and 10 atmospheres, said conditions being correlated in the known manner within said ranges to avoid substantial cracking of said olefins, discontinuing said contact when the bromine number of the resulting product corresponds to the content of said straight chain amylenes in the mixture whereby said branched chain olefins are selectively converted to isopentane, and recovering the said straight chain olefins in concentrated form from the isopentane so produced.
